ATTORNEY'S

UNITED STATES PATENT OFFICE.

JOHN WALKER, OF CLEVELAND, OHIO.

PULLEY OR WHEEL.

SPECIFICATION forming part of Letters Patent No. 288,522, dated November 13, 1883.

Application filed May 25, 1883. (No model.)

To all whom it may concern:

Be it known that I, JOHN WALKER, of the city of Cleveland, county of Cuyahoga, and State of Ohio, have made certain Improvements in Pulleys and Wheels, of which the following is a specification.

This invention relates to certain improvements in sectional pulleys and wheels of various descriptions; and it consists in improved means for holding the sections together, as will hereinafter fully appear.

In the accompanying drawings, forming a part hereof, Figure I is a side elevation of the improved pulley. Fig. II is a sectional view 15 of the same, taken on the dotted line $\alpha\alpha$. Fig. III is a partly sectional edge view. Figs. IV to VII, inclusive, are views of parts of the pulley on an enlarged scale.

Similar letters of reference indicate similar 20 parts in all the figures.

A, B, and C are respectively the hub, arms, and rim of the pulley, which parts in themselves are of ordinary description. The pulley shown in the drawings is in two sections; but 25 it may be made in three or more, if desired.

In order that the pulley may be easily divided into sections before or after boring and turning, the rim, hub, and arms are cast with slots a , which are of such length as to give 30 narrow junction-pieces b , to be afterward forced asunder.

D are tapered dovetailed projections cast

on the rim and the hub of the pulley or wheel, over which binding-clamps E are forced. The taper of the projections D and the binding-clamps is shown in Figs. III, V, and VII, and by reference to Figs. I, IV, V, and VI it will be seen that the faces c of the binding-clamps are in contact with the depressed portions d of the projections, and also that the surfaces e and f , respectively, of the clamps and projections are in contact.

By having all the faces of the clamps and projections in contact, as described, the clamps are prevented from being curved or distorted 45 in shape when forced on the projections.

It will be understood that in driving the binding-clamps on the projections the sections of the pulley are drawn together and the faces 50 e and f brought in close contact.

I claim as my invention—

1. A pulley or wheel in sections, having dovetailed projections, substantially as described, combined with similarly-shaped binding-clamps, substantially as specified. 55

2. A pulley or wheel in sections, having tapered dovetailed projections, substantially as described, combined with similarly-shaped binding-clamps, substantially as specified.

JOHN WALKER.
